UNITED STATES PATENT OFFICE

151,621

DESIGN FOR A COMBINED NUTCRACKER AND TRAY

Irwin W. Green, Bell Gardens, Calif.

Application March 26, 1946, Serial No. 127,950

Term of patent 3½ years

(Cl. D44—1)

To all whom it may concern:

Be it known that I, Irwin W. Green, a citizen of the United States, residing in Bell Gardens, in the county of Los Angeles and State of California, have invented a new, original, and ornamental Design for a Combined Nutcracker and Tray, of which the following is a specification, reference being had to the accompanying drawing, forming part thereof.

Fig. 1 is a perspective view of a combined nutcracker and tray, showing my new design.

Fig. 2 is a rear elevational view on a reduced scale.

The essential features of my design reside in the tray and animal perch combination.

I claim:

The ornamental design for a combined nut-

cracker and tray, substantially as shown and described.

IRWIN W. GREEN.
